MANIFOLDING

Frank G. Wellner, Chicago, Ill., assignor to Auto-graphic Register Company, Hoboken, N. J., a corporation of New Jersey

Application May 25, 1936, Serial No. 81,648

10 Claims. (Cl. 282—12)

This invention relates to manifolding, and, more particularly, to a manifolding pile containing two groups of record strips with provisions for reproducing certain writings on all of the strips and other writings on only some of the strips. The manifolding pack of the present invention is particularly adapted for use with telegraphic typewriters.

Heretofore, with the use of telegraphic typewriters, it was the custom to receive at the factory, for instance, an order for goods from a branch house itemizing the goods desired to be shipped and giving the name of the shipper, the route, etc. Multiple copies were made of these orders, so that one could be given to the stock clerk, one to the shipping clerk, and the rest to others. It was found impractical, however, to write the bill of lading, on which the goods were to be shipped, at the same time, because much of the information desired on the bill of lading is not available at the time of writing the order; frequently some of the goods could not be shipped at the same time as the main order, and there was no necessity of itemizing the goods in the shipment on the bill of lading.

There are, however, some indicia required on the bill of lading which are available at the time the order is made out, such as the name of the customer, his address, and the method of shipping.

The present inventor makes provision for writing this available information on the bill of lading simultaneously with the writing of the order, and further makes provision for permitting the factory orders to be removed from the superposed copies of the bill of lading after the order has been written, leaving the copies of the bill of lading secured together in superposed position with carbon paper interleaved, so that it may be quickly and easily filled out when the necessary information is available and the goods are ready for shipment.

To do this, continuous strips containing the bills of lading are interposed with transfer strips, and then inserted between the transfer strips and the bills of lading, and disposed on the top bill of lading are the factory order strips. These factory orders have on their backs transfer material overlying the portions of the bill of lading which are to contain the indicia common to the factory orders and the bills of lading.

These factory orders perform the double function of blocking out, i. e. preventing writing on, the bills of lading of the indicia which are not to be transferred thereto, and of transferring to the

bills of lading the material which is common to the bills of lading and the factory orders.

According to the present invention, when the two kinds of record strips and continuous transfer strips are superposed as above outlined, they are secured together in registration so as to travel as one, and when, as in the preferred form of the invention, the strips are divided transversely by weakened severance lines into sheet-lengths, each sheet-length contains a securing means. To facilitate the separation and removal of the factory orders from the bills of lading after the factory orders have been written, the securing means is located in a stub portion in the factory order defined by a weakened line so that the factory orders may be pulled from the pile of bill of lading sheets.

So that the strips may be fed positively, as in the telegraphic typewriter, the side margins of the strips may be provided with rows of apertures to engage pin-like feeding devices carried by the typewriting machine.

Other features and advantages will hereinafter appear.

In the accompanying drawing—

Figure 1 is a perspective view of the manifolding pile of the present invention.

Fig. 2 is a plan view of the pile, the strips being torn away successively and folded back to show the relation in the pile of the various strips.

Fig. 3 is a plan view of a suitable factory order, a succession of which is carried by some of the record strips in the pile.

Fig. 4 is a plan view of a pile of connected bill of lading sheets with the corners of some of the sheets folded back to show the position of one of the transfer sheets between the bills of lading.

As shown in the accompanying drawing, the manifolding pile of the present invention comprises a plurality of continuous strips 10 containing suitable printing and constituting, in the form shown, factory order blanks, and a plurality of continuous record strips 11 containing suitable printing and constituting, in the form shown, a succession of bills of lading. In addition to the strips 10 and 11, the pile contains continuous transfer strips 12. The strips 10, 11 and 12 are superposed in a manner which will be explained below, and are provided with transverse lines of weakness 13 along which the strips may be torn to produce sheets 10a, hereinafter referred to as factory orders, and sheets 11a, hereinafter referred to as bills of lading. Preferably, the pile of strips 10, 11 and 12 are zigzag folded along the lines of perforations 13 to form a pack 14 shown

in Fig. 1. In superposing the strips 10, 11 and 12, the carbon or transfer strips 12 are placed under the bill of lading strips 11. Instead of being placed directly over the next lower bill of lading strip 11, however, the latter and the carbon strip 12 are separated by the factory order strips 10, and, so long as these strips 10 are interposed between the carbon strips and the bills of lading, the carbon strips are prevented from transferring impressions to the bills of lading. The uppermost bill of lading strip 11 is likewise covered by the uppermost factory order strip 10, so that the ink impressions from the typewriter ribbon will not be produced on the bill of lading.

15 It will be seen, therefore, that, so long as the factory orders are in place in the pile, the function of the carbon strip 12 is to transfer the impressions to the underlying factory orders, and the latter prevent the carbon strip 12 from transferring impressions on the bills of lading.

Accordingly, such items, as the kind, quantity, and quality of the merchandise being ordered, will not appear on the bill of lading but only on the factory order strips. There are, however, certain indicia which are required both on the factory order and on the bill of lading, such as the name of the consignee and his address and the shipping instructions. To permit the transfer of this indicia to the bill of lading, each of the 30 shipping order strips has on its back face 15 a coating 16 of transfer material covering the area of the bill of lading containing the indicia which it is to receive during the writing of the factory order. This coated area 16 lies directly under the places on the factory order which are to receive the common indicia.

After a factory order has been written, the strips 10, 11 and 12 may be severed along the lines of weakness 13 to produce a group of sheets 40 containing factory orders, bills of lading, and transfer sheets.

To maintain the strips in registration and so that they will feed as one, the strips are held together at definite intervals by staples 17. There 45 is at least one staple for each superposed set of sheets so that when the group of sheets is severed from the pile, it will be held together as long as desired.

After the group of sheets has been severed 50 from the pile, the factory orders 10a may be removed from the pile leaving the bills of lading 11a and carbon sheets 13a secured together as a unit to receive manifold typewriting operations when the order has been filled and the goods 55 are ready for shipment.

To permit this separation of the factory orders, the staples 17 are located in stub portions 18 in the factory orders. Each stub portion is defined by a line of weakness 19 along which the factory 60 order 10a may be torn to remove it from the pile. To permit this to be done with ease, the factory orders have at one side a margin 20 projecting beyond the adjacent edges 21 and 22 of the carbon and bill of lading strips 12 and 11 respectively, the projecting portion forming a finger-piece by means of which all of the factory orders 65 may be grasped as one to be torn from the stub portion 18.

To permit the feeding of the pile of strips to be 70 controlled positively, one or more of the strips may be provided with rows of pin-engaging apertures 23 in one or more lateral margins of the strip. As shown, both the strips 10 and 11 have the pinwheel-engaging apertures at one side of

the pile, while only the strips 10 have the apertures 23 at both sides of the pile.

It should be understood that the invention is not limited to the particular embodiment illustrated in the accompanying drawing nor to the purpose or use of the respective strips, and that the terms "factory order" and "bill of lading" have been used in reference to the specific embodiment of the invention which is illustrated for convenience, it being an embodiment which has 10 been found particularly practical and useful.

Variations and modifications may be made within the scope of this invention and portions of the improvements may be used without others.

I claim:

1. A manifolding pile comprising a plurality of continuous record strips in superposed relation; a plurality of continuous transfer strips interleaved with the record strips; other continuous record strips having on their back surfaces transfer material covering certain areas only in which type impressions are to be made on all of the strips, each of said second-named record strips overlying one of said first-named record strips to receive type impressions, the top strip direct 20 and the other strips by transfer from the transfer strips and transfer material in the said certain areas, and to simultaneously block out the transfer type impressions of the remaining part of the first-named record strips; and means for securing the strips together to move as one, the second-named record strips being mounted in the pile for easy removal therefrom to leave the first-named record strips interleaved with the transfer strips for further manifolding.

2. A manifolding pile comprising a plurality of continuous record strips in superposed relation; a plurality of continuous transfer strips interleaved with the record strips, other continuous record strips overlying one of the first-named record 40 strips; transfer material between the second-named record strips and the first-named record strips covering certain areas only in which type impressions are to be made simultaneously on all the strips, the type impressions being received by 45 the top strip direct and the other strips by transfer from said transfer strips and material and the second-named record strips simultaneously blocking out the transfer of type impressions on the remaining parts of the first-named record 50 strips; means for securing all of the strips together to travel as one; and means whereby the pile can be severed into sets of forms, the second-named record strip being detachably mounted in the set of forms for removal therefrom to leave 55 the first-named record strips interleaved with the transfer strips for further manifolding.

3. A manifolding pile comprising a plurality of continuous record strips in superposed relation; a plurality of continuous transfer strips interleaved 60 with the record strips, other continuous record strips overlying one of the first-named record strips; transfer material between the first-named record strips and the first-named record strips covering certain areas only in which type impressions are to be made simultaneously on all the strips, the type impressions being received by the top strip direct and the other strips by transfer from said transfer strips and material and the second-named record strips simultaneously blocking 65 out the transfer of type impressions on the remaining parts of the first-named record strips; and means for securing all of the strips together to travel as one, all of the strips being divided into uniform sheet lengths by transverse lines of 70 75

weakness, along which a pile may be severed to form sets of superposed sheets, the second-named record strip being detachably mounted in the set for removal therefrom to leave the first-named record strips interleaved with the transfer strips for further manifolding.

4. A manifolding pile comprising a plurality of continuous record strips in superposed relation; a plurality of continuous transfer strips interleaved with the record strips, other continuous record strips overlying one of the first-named record strips; transfer material between the first-named record strips and the first-named record strips covering certain areas only in which type impressions are to be made simultaneously on all the strips, the type impressions being received by the top strip direct and the other strips by transfer from said transfer strips and material and the second-named record strips simultaneously blocking out the transfer of type impressions on the remaining parts of the first-named record strips; and means for securing all of the strips together to travel as one, all of the strips being divided into uniform sheet lengths by transverse lines of weakness, along which a pile may be severed to form sets of superposed sheets, and the securing means holding all of said sheets together in a set, the second-named record sheets being formed with additional lines of weakness extending in the body of the form adjacent the securing means whereby the sheets can be removed from the secured sets of sheets thereby leaving the first-named record sheets interleaved with the transfer sheets for further manifolding.

5. A manifolding pile comprising a plurality of continuous record strips in superposed relation; a plurality of continuous transfer strips interleaved with the record strips, other continuous record strips overlying one of the first-named record strips; transfer material between the first-named record strips and the first-named record strips covering certain areas only in which type impressions are to be made simultaneously on all the strips, the type impressions being received by the top strip direct and the other strips by transfer from said transfer strips and material and the second-named record strips simultaneously blocking out the transfer of type impressions on the remaining parts of the first-named record strips; and means for securing all of the strips together to travel as one, all of the strips being divided into uniform sheet lengths by transverse lines of weakness along which the pile may be severed to form sets of superposed sheets, and the securing means holding all of said sheets together in a set and being located in a portion of each sheet of the second-named record strip which portion is weakened for easy removal of the second-named record strips from the set, thereby leaving the first-named record strips secured together and interleaved with transfer sheets for subsequent manifolding writing operations.

6. A manifolding pile comprising a plurality of continuous record strips in superposed relation; a plurality of continuous transfer strips interleaved with the record strips, other continuous record strips overlying one of the first-named record strips; transfer material between the first-named record strips and the first-named record strips covering certain areas only in which type impressions are to be made simultaneously on all the strips, the type impressions being received by the top strip direct and the other strips by

transfer from said transfer strips and material and the second-named record strips simultaneously blocking out the transfer of type impressions on the remaining parts of the first-named record strips; and means for securing all of the strips together to travel as one, all of the strips being divided into uniform sheet lengths by transverse lines of weakness, along which the pile may be severed to form sets of superposed sheets, and the securing means holding all of said sheets together in a set and being located in a portion of each sheet of the second-named record strip which portion is weakened for easy removal of the second-named record strips from the set, thereby leaving the first-named record strips secured together and interleaved with transfer sheets for subsequent manifolding writing operations, the strips being provided with marginal rows of pin-engaging apertures.

7. A manifolding pile comprising a plurality of continuous record strips in superposed relation; a plurality of continuous transfer strips interleaved with the record strips, other continuous record strips overlying one of the first-named record strips; transfer material between the first-named record strips and the first-named record strips covering certain areas only in which type impressions are to be made simultaneously on all the strips, the type impressions being received by the top strip direct and the other strips by transfer from said transfer strips and material and the second-named record strips simultaneously blocking out the transfer of type impressions on the remaining parts of the first-named record strips; and means for securing all of the strips together to travel as one, all of the strips being divided into uniform sheet lengths by transverse lines of weakness, along which the pile may be severed to form sets of superposed sheets, and the securing means holding all of said sheets together in a set and being located in a portion of each sheet of the second-named record strip, which portion is weakened for easy removal of the second-named record sheets from the set, thereby leaving the first-named record strips secured together and interleaved with transfer sheets for subsequent manifolding writing operations, the sheets of the second-named record strips projecting beyond the carbon sheets and the sheets of the first-named record strips in a severed set of sheets.

8. A manifolding pack comprising a first record sheet; a second record sheet in superposed relation; a transfer sheet interleaved with said record sheets; a third record sheet overlying the first record sheets; transfer material between the third record sheet and the first record sheet covering certain areas only in which type impressions are to be made simultaneously on all of the record sheets, the third record sheet receiving type impressions from the second record sheet by transfer from said transfer sheet and blocking transfer of type impressions on the remaining parts of the first record sheet; and means for securing all of the sheets together, the second-named record sheet being detachably mounted in the pack for removal therefrom to leave the first and second record sheets with the transfer sheet interleaved therebetween for further manifolding operations.

9. A manifolding pack comprising a plurality of record sheets in superposed relation; a plurality of carbon sheets interleaved with the record sheets; a plurality of other record sheets, each overlying one of the first-named record sheets; transfer material between the second-named rec-

ord sheets and the first-named record sheets covering certain areas only in which type impressions are to be made simultaneously on all of the record sheets; the record sheets receiving type impressions, the top sheet direct and the other sheets by transfer by said carbon sheets and transfer material, and the second-named record sheets simultaneously blocking out the transfer of type impressions on remaining parts of the first-named record sheets; means for securing all of the sheets together; and means, including weakened lines in the second-named record sheets, whereby the latter can be removed from the pack, thereby leaving the first-named record sheets interleaved with the carbon sheets for further manifolding operations.

10. A manifolding pack comprising a plurality of record sheets in superposed relation; a plurality of carbon sheets interleaved with the record sheets; a plurality of other record sheets, each overlying one of the first-named record

sheets; transfer material between the second-named record sheets and the first-named record sheets covering certain areas only in which type impressions are to be made simultaneously on all of the sheets; the record sheets receiving type impressions, the top sheet direct and the other sheets by transfer from the carbon sheets and transfer material, and the second-named record sheets simultaneously blocking out the transfer of type impressions on the remaining parts of the first-named record sheets; means for securing all of the sheets together; and means, including weakened lines in the second-named record sheets, whereby the latter can be removed from the pack, thereby leaving the first-named record sheets interleaved with the carbon sheets for further manifolding operations, a margin of the second-named record sheets projecting beyond the first-named record and carbon sheets.
